L. L. KELSEY,
SAND TRAP FOR WELLS,
APPLICATION FILED JULY 18, 1921.

1,431,006.

Patented Oct. 3, 1922.

UNITED STATES PATENT OFFICE.

LESTER LAUREL KELSEY, OF PERSHING, OKLAHOMA.

SAND TRAP FOR WELLS.

Application filed July 18, 1921. Serial No. 485,709.

To all whom it may concern:

Be it known that I, LESTER LAUREL KELSEY, a citizen of the United States, residing at Pershing, in the county of Osage and State 5 of Oklahoma, have invented certain new and useful Improvements in Sand Traps for Wells; and I do declare the following to be a full, clear, and exact description of the invention, such as will enable others skilled 10 in the art to which it appertains to make and use the same.

This invention relates to an improved device which is designed for trapping sand and separating it from oil or other liquid, 15 the same being designed for installation in a well at a point between the working barrel and the usual stationary perforated anchoring pipe at the lower end of the barrel.

The principal object of the invention is 20 to generally improve upon traps of this class by the provision of one of extreme simplicity and durability which is made up of a plurality of communicating compartments arranged one above the other and each being 25 equipped with restricted inlets and outlets and the inlet being closed by an upstanding strainer which extends into the interior of the compartment and terminates short of the upper end of this compartment, this 30 strainer being considerably small in diameter when compared to the pipe-section forming the chamber and thus providing a pocket at the bottom of the chamber for collecting the sand.

Another object of the invention is to 35 devise a sand trap for wells which is constructed from ordinary pipe-sections connected together by especially formed couplings including imperforate disc-like sections and carrying integral upstanding tubular perforated portions constituting the aforesaid strainers. Hence, it will be seen that the several pipe sections which go to make up the device can be quickly separated by 40 simply disconnecting them from the coupling and the sand and other gritty material can be easily and readily removed.

Other objects and advantages of the invention will be apparent during the course of 50 the following description.

In the accompanying drawings forming a part of this specification and in which like numerals are employed to designate like parts throughout the same:

55 Figure 1 is a central vertical sectional

view through a device constructed in accordance with the invention.

Figure 2 is a similar view with parts in elevation showing the relative proportions more clearly. 60

Figure 3 is an enlarged transverse section taken substantially on the plane of the line 3—3 of Fig. 1.

As previously indicated, the improved sand trapping device is designed to be installed in the well conduit at a point between the working barrel and the usual perforated anchoring pipe at the lower extremity of the well. In the preferred embodiment of the invention, I make use of a plurality of ordinary pipe sections 1 and detachably connect these sections with one another by special couplings 2, thus providing an arrangement which permits the several parts of the device to be easily and readily disconnected from one another for making 70 repairs and for removing the sand and other gritty material which has collected in the various compartments. Referring specifically to the formation of the couplings, it will be seen that each one includes a disc-like imperforate portion 3, the peripheral portion of which is surrounded by an annular internally screw-threaded flange 4 extending above and below the upper and lower faces 80 of this disc-like portion as shown and providing means for connection of two sections of pipes together. At its center, this portion 3 of the coupling is formed with an opening 5 which, in one instance serves as an 90 inlet for the chamber and in another instance serves as an outlet for the same chamber. Rising from the center of the part 3 and communicating with the opening 5 is an upstanding tubular part 6 which is closed at its upper end and is formed with a plurality of perforations 7, permitting it to serve in the capacity of a strainer. It is to be noted that this tubular strainer 6 is much 95 smaller in diameter than the pipe section 1 which surrounds it and therefore provides considerable space between itself and the inner wall of the section to permit considerable quantity of sand to be collected on the upper faces of the couplings. It is also to 100 be noted that the strainers 6 terminate short of the upper closed ends of the chambers so as to insure that the sand will fall down onto the upper face of the lower coupling of the chamber instead of being carried upwardly 105

110

with the liquid and into the next chamber which might otherwise occur. From the foregoing it will be seen that the various parts are especially proportioned as more clearly indicated in Fig. 2, to insure effective results. It is to be pointed out here that the uppermost chamber is not closed at its upper end by a coupling and instead of having the tubular portion 6 therein closed and per-
10 forated at its upper end, this portion is entirely open and a conventional type of ball check valve indicated generally by the numeral 8 is secured on the upper open end. It is yet to be pointed out that the device in
15 addition to embodying the aforesaid parts, includes the reducers 9 which are connected to the upper and lower chambers and these reducers carry suitable couplings 10 which are connected with the anchoring pipe in one
20 instance and the working barrel in another.

A careful consideration of the description taken together with the drawings will give a clear understanding of the operation. However, to remove all doubt, I will again state
25 that in actual use the device is installed in the well conduit at a point between the working valve and the usual perforated anchoring pipe at the lower end of the well conduit. The oil, or other fluid, passes
30 through the perforated anchoring pipe in the usual way and flows upwardly until it reaches the lower chamber of my sand trapping device. As it enters the lower chamber, the liquid is strained by means of the up-
35 standing pipe 6 in this compartment and a considerable portion of the sand and grit is removed from the liquid and is dropped to the bottom of this compartment and it settles on the upper face of the lowermost
40 coupling 2. However, a single compartment, I have found is not sufficient to clarify the liquid as much as desired. Hence, it will be seen that as it passes upwardly through the other compartments and is acted on in a
45 similar way, when it enters the working

barrel, there is little or no sand left that will interfere with the pumping mechanism. Hence, the valves and packing and cups of such mechanism will last much longer than is the case with the present formation of 50 pumps. I have found that the liquid after passing through the first two compartments has practically all of the sand removed therefrom. Consequently, when it passes through the valved straining device 6 in the upper 55 compartment, the small quantity of sand carried with the liquid will hardly interfere with the valve carried by this strainer.

Since probably the best results may be obtained with the construction and arrangement herein shown and described, this is taken as the preferred embodiment of the invention. However, I wish it to be understood that minor changes coming within the scope of the subjoined claims may be resorted to. 60

I claim:

1. The combination with a working barrel, a standing valve therefor, and a strainer below said valve and working barrel; of an enlarged conduit interposed between and 70 directly connected to said barrel and strainer, a plurality of vertically spaced transverse partitions arranged in said conduit and dividing it into a plurality of superposed vertically aligned compartments, all of said 75 partitions being disposed below said standing valve to separate the sand from the oil before it reaches said valve, and a plurality of sand trapping or separating tubes rising rigidly from and carried solely by said partitions, said tubes extending into and terminating adjacent the upper ends of each 80 of said compartments.

2. The structure set forth in claim 1, wherein the standing valve is carried on the 85 upper end of the uppermost separating tube.

In testimony whereof I have hereunto set my hand.

LESTER LAUREL KELSEY.
